CLOTHES HAMPER

Earl S. Tupper, Smithfield, R.I., assignor to Tupper Corporation, North Smithfield, R.I., a corporation of Delaware

Application July 11, 1958, Serial No. 51,755

Term of patent 14 years

(Cl. D58—4)

I claim:

The ornamental design for a clothes hamper, substantially as shown.
